UNITED STATES PATENT OFFICE.

WILLIAM DONAHEY, OF CHICAGO, ILLINOIS.

DESIGN FOR A DOLL.

57,601.

Application filed December 20, 1920. Serial No. 432,094. Term of patent 14 years.

Patented Apr. 26, 1921.

To all whom it may concern:

Be it known that I, WILLIAM DONAHEY, a citizen of the United States, residing at Chicago, in the county of Cook and State of Illinois, have invented a new, original, and ornamental Design for a Doll, of which the following is a specification, reference being had to the accompanying drawing, forming a part thereof.

The figure is a perspective view of a doll showing my new design.

I claim:

The ornamental design for a doll, as shown.

WILLIAM DONAHEY.
